CIRCUIT BREAKER

Ture Lindstrom, Edgewood, and John W. May,
Pittsburgh, Pa., assignors to Westinghouse
Electric & Manufacturing Company, East Pitts-
burgh, Pa., a corporation of Pennsylvania

Application October 21, 1941, Serial No. 415,912

9 Claims. (Cl. 200—88)

This invention relates to circuit breakers and more particularly to circuit breakers of the type that are tripped instantaneously on overloads above a predetermined value and after a time delay on lesser overloads.

It is an object of this invention to provide a circuit breaker having an improved trip device which is of simple construction, reliable in operation and inexpensive to manufacture.

Another object of the invention is the provision of a circuit breaker having an improved trip mechanism in which a trip member is operated at times free of a biasing means, and at other times in opposition to said biasing means.

Another object of the invention is to provide a circuit breaker having an improved trip mechanism in which a bimetal element operates when heated a predetermined amount to permit a trip member to unlatch itself from a biasing means which normally opposes operation of the trip member.

Another object of the invention is to provide a circuit breaker with an improved trip device wherein a trip member is provided with biasing means disconnectible therefrom under certain conditions and having means to prevent disconnection of the biasing means under certain other conditions.

Another object of the invention is to provide a circuit breaker having an improved trip device in which a latch is provided for normally latching a biasing means to a trip member, said latch being operable to disconnect the biasing means under certain abnormal circuit conditions and which is provided with another latch to prevent disconnection of the biasing means under certain other abnormal circuit conditions.

A further object of the invention is to provide a circuit breaker with an improved trip mechanism wherein a thermal element operates a latch which permits a trip member to automatically disconnect itself from a biasing means.

An object of the invention is the provision of a circuit breaker having an improved electromagnetically responsive and thermally responsive trip device which is operable to cause automatic opening of the breaker instantaneously upon the occurrence of overloads above a predetermined magnitude and after a time delay introduced by a thermally responsive element in response to overloads below the predetermined magnitude.

Another object of the invention is the provision of a circuit breaker with an improved trip device having a current responsive electromagnetic

means which is operable to cause automatic opening of the breaker, and a spring biased member releasably connected to a trip element operated by the electromagnetic means for normally opposing operation of the trip element but which is caused to be released from the spring biased member by a thermally responsive element when the thermally responsive element is heated a predetermined amount in response to overload current.

10 Another object of the invention is the provision of a circuit breaker having an improved trip device as previously described and wherein the spring biased member which opposes operation of the trip element is releasably connected thereto by an anti-friction latching means which reduces to a minimum the operating effort required of the thermally responsive element to cause unlatching of the trip element.

15 The present invention constitutes a further development and improvement over the invention disclosed and claimed in the copending application of John W. May, Serial No. 424,421, filed December 28, 1941, now Patent No. 2,357,217, issued Aug. 29, 1944, and assigned to the assignee of the present invention.

20 The novel features that are considered characteristic of the invention are set forth in particular in the appended claims. The invention 30 itself, however, both as to structure and operation, together with additional objects and advantages thereof, will be best understood from the following detailed description of several embodiments thereof when read in conjunction with the 35 accompanying drawings, in which:

Figure 1 is a vertical sectional view through the center pole of a three-pole circuit breaker embodying the features of the invention.

Fig. 2 is a fragmentary horizontal sectional view at an enlarged scale taken substantially on line II—II of Fig. 1 and showing the trip mechanism for two of the poles.

Fig. 3 is a vertical sectional view through the trip device taken substantially on line III—III of Fig. 2, showing the trip member operated after it has been caused to be released from the spring biased member by operation of the thermally responsive element.

45 Fig. 4 is a vertical sectional view similar to Fig. 3 but showing the trip member in operated position without having the biasing means disconnected therefrom.

50 Fig. 5 is a vertical sectional view similar to Fig. 3 but showing a modification of the trip de-

vice of the breaker. The parts are illustrated in their untripped positions.

Fig. 6 is a vertical sectional view similar to Fig. 5 but showing the parts in the positions they assume after the bimetal element has caused the release of the trip lever from the spring biasing means.

Referring to Fig. 1, the circuit breaker is of the multipole type and is provided with a common operating mechanism mounted on a main frame 17 (Fig. 1) secured to the center portion of a base 11. The base is of insulating material and the main frame 17 is secured thereto by means of bolts 21 and 23. The frame 17 comprises a pair of spaced substantially parallel members rigidly joined adjacent the base 11 by a cross member 19 and at the outer end by a cross member 25. A casing 13 (shown by dotted and dash lines) may be provided to enclose the circuit breaker.

A contact arm 30 for the center pole of the breaker is provided with a pair of spaced arms 31 disposed one on each side of a connector 27 rigidly secured to the cross member 19 and to the base 11 by the bolt 23. The arms 31 are pivotally supported on a short shaft 29 extending through a suitable opening in the connector 27 and through bearing openings provided therefor in the sides of the frame 17.

The contact arm 30 pivotally carries a main contact member 47 supported on a pivot 49 mounted in spaced projections 51 (only one being shown) of the contact arm 30. A movable contact 33 secured to the contact member 47 cooperates with a stationary main contact 39 mounted on a conductor 41 which is secured to the base 11 by means of bolts 43.

An arcing contact member 55 is pivoted on a pivot pin 57 supported in a pair of spaced projections 59 (only one being shown) on the contact arm 30. The arcing contact member 55 has secured thereto an arcing contact shoe 35 cooperating with a stationary arcing contact 37 which is secured to an arcing horn 36. The arcing horn 36 is secured to the conductor 41 by means of screws 38. The conductor 41 is bent at right angles and projects through an opening in the base 11 to form a terminal connector 45.

Contact pressure is provided for the main contacts 33-39 by means of a spring 53 compressed between a spring seat on the contact arm 30 and a spring seat on the main contact member 47. In a similar manner the arcing contacts 35-37 are provided with spring pressure through the agency of a spring 63 surrounding a rod 61 which is pivotally connected to the arcing contact member 55. The spring 63 is compressed between a washer 65 seated on a shoulder of the rod 61 and a spring seat on the contact arm 30. The rod 61 slidably projects through an opening in the contact arm 30 and has a nut 75 screwed onto its outer end.

As previously stated, the circuit breaker is of the multipole type, and each of the poles of the circuit breaker has a stationary contact means and a movable contact means similar to that of the center pole shown in Fig. 1 and described above, except that the contact arms of the outer poles do not have extending pivot arms corresponding to the arms 31 of the center pole contact arm 30. Each of the three contact arms is securely clamped to a steel tie bar 67 by means of a clamp 70 and a bolt 71, as shown on the center pole contact arm 30, so that all of the three contact arms and the movable contacts

carried thereby are operated simultaneously. The movable contacts of the poles are insulated from each other by a sheath of insulating material surrounding the tie bar and disposed between the tie bar 67 and the clamp portions of the contact arms.

When the contact arm 30 for the center pole is rotated in a clockwise direction (Fig. 1) to open the contacts, as will presently be described, the springs 53 and 63 rock the contact members 47 and 55, respectively, counterclockwise about their pivots. The counterclockwise movement of each main contact member 47 is limited by a projection 73 thereon striking the body of the contact arm 30, and the counterclockwise movement of each arcing contact member 55 is limited by the nut 75 on the rod 61 striking the contact arm 30. The adjustment of the nut 75 on the rod 61 is such that the main contacts 33-39 open shortly before the arcing contacts 35-37 open.

The arc resulting from the rupture of the current is drawn into an arc extinguisher 76 where it is broken up into a plurality of small arcs and these arcs quickly cooled and extinguished. The arc extinguisher 76, of which there is one provided for each pole of the breaker, is of a well known type and comprises, generally, a stack of slotted plates disposed adjacent the path of travel 30 of the arcing contact 35. The plates serve to draw the arc toward the ends of the slots where it is extinguished.

The electrical circuits for the several poles of the breaker are the same, the circuit of each 35 pole extending from the terminal 45 through the conductor 41, the stationary main contact 39, the movable main contact 33, main contact member 47, a flexible shunt conductor 79 connecting the main contact member 47 and the connector 27, 40 a connector 72 secured to the connector 27 by means of bolts 74, a heating conductor 78 having its upper end secured to the connector 72 and its lower end connected to one end of a magnet coil 80, and through the magnet coil 80 to a terminal connector 83. The terminals 45 and 83 serve to connect the breaker in an electrical circuit.

The circuit for the arcing contacts extends from the conductor 41 through the arcing contacts 37 and 35, the arcing contact member 55, a flexible shunt conductor 77 to the main contact member 47 and thence over the previously described circuit to the terminal 83.

The contact arm 30 for the center pole is biased in a clockwise direction toward open position by a pair of springs 85, only one of which is shown, having one end connected to the contact arm 30 near its free end and the other end anchored on a fixed pivot pin 87 supported in the main frame 17. Under normal circuit conditions the contact arm 30 is releasably restrained in its closed contact position (Fig. 1) by means of a toggle and linkage arrangement of the common operating mechanism which toggle and linkage is collapsible to cause opening of the contacts.

The mechanism linkage comprises a lever 89 pivotally mounted on a fixed pivot 91 supported in the main frame 17, and this lever comprises a pair of levers rigidly joined by a cross member 117. The lever 89 is connected to the arms 31 of the center pole contact arm 30 by a main operating toggle comprising a toggle link 93 having one end pivoted on a pin 101 in the lever 89 and a toggle link 95 having one end pivoted on a pivot pin 99 in the arms 31, the toggle links 93 and 95

being pivotally connected by a knee pin 91. The link 95 comprises a pair of links rigidly joined by a cross bar 115. The free end of the lever 89 is connected by a link 103 to one arm of a lever 105 pivoted on the fixed pivot 91. The other arm of the lever 105 is pivotally connected to a link 107 of a tripping toggle comprising the link 107 and a link 109 pivoted on a fixed pivot 113 mounted in the frame 17, the toggle links 107 and 109 being pivotally connected by a knee pin 111. The toggle link 107 comprises a pair of links joined by a yoke 119 having a bent portion to which is secured an extension 121 of insulating material. The toggle link 109 comprises a pair of links joined near the pivot 113 by a yoke 123 having formed portions 125 and 127 thereon. The lever 103 and the link 103 each comprises a pair of members joined by a yoke substantially as illustrated. The extension 121 on the yoke 119 cooperates with a manually operable handle 141 to trip the breaker in a manner to be later described.

The linkage just described serves to releasably hold the contact assemblage in closed contact position. When the contact arm 30 is in the closed contact position, the main operating toggle 93-95 is over-center above a line through the centers of the pins 99 and 101, and the toggle comprising the link 93 and 95 and the lever 89 is over-center above a line through the center of the pin 99 and the fixed pivot 91. The upward over-center movement of the main operating toggle 93-95 is limited by the projecting end of the link 93 engaging the cross bar 115. With the main operating toggle 93-95 and the toggle 85-93 and 89 in their over-center positions the springs 85 bias the lever 89 in a clockwise direction. Movement of the lever 89, however, is normally prevented by the tripping toggle 107-109 which is biased over-center to the left of a line drawn through the center of the fixed pivot 113 and the point of connection of the toggle link 107 and the lever 105, by means of a spring 120 tensioned between the yoke 119 and the fixed pivot 113. The over-center position of the tripping toggle is adjustably determined by a screw 129 in the cross member 25. The tripping toggle 107-109 in its over-center position, acting through the lever 105 and link 103, prevents clockwise rotation of the lever 89 and consequently holds the movable contact assemblage in the closed contact position against the action of the springs 85.

The tripping toggle 107-109 is adapted to be moved outwardly over-center toward collapsed position to cause opening of the contacts by a trip device, indicated generally by the reference numeral 133, acting through a trip rod 135. The trip rod 135 is slideable vertically through the coil of a shunt trip electromagnet enclosed in a casting 138 secured to the main frame 17. The shunt trip coil is adapted to be energized over a shunt circuit (not shown) or by a manually controlled switch to operate the trip rod 135 from a remote point in a manner well known in the art.

The trip device 133, when actuated in response to an overload current, thrusts the trip rod 135 upwardly, at which movement the upper end of the rod strikes the formed portion 127 of the toggle link 109 and rocks said toggle link clockwise about the fixed pivot 113. The clockwise movement of the link 109 causes collapse of the tripping toggle 107-109 which permits the springs 85 to rock the contact assemblage clockwise to open the contacts. The main operating

toggle 93-95 does not immediately collapse, but moves as a unitary linkage transmitting the movement of the contact arm 30 to rock the lever 89 in a clockwise direction. This movement of the lever 89 is transmitted through the linkage 103-105 to complete the collapse of the tripping toggle 107-109.

The clockwise or opening movement of the contact arm 30 is arrested by projections (not shown) thereon striking a portion 137 of the main frame 17. At this time the inertia of the linkage starts the toggle 93-95 over-center in a direction to cause its collapse. By the time the knee pin 91 of the main toggle has passed below the line 99-101 the weight of the linkage and parts causes the main toggle 93-95 to collapse and causes the lever 89, link 103, lever 105 and the tripping toggle 107-109 to be automatically reset to their normal positions as shown in Figure 1. The main operating toggle 93-95 remains in collapse condition until the contacts are closed.

The contacts can be closed by manual operation of the previously mentioned operating handle 141. The handle is rotatably mounted in a bracket 143 of insulating material secured to the outer end of the main frame 17. A link 151 connected to a crank on the shaft of the handle is adapted to be thrust downwardly (Fig. 1) upon clockwise or closing movement of the operating handle 141. The link 151 is notched at its lower end and engages an hourglass shaped roller 153 rotatably mounted on a cross member 147 rigidly connecting the outer end of a pair of levers 145. The levers 145 straddle the frame 17 and are pivotally supported on the ends of the fixed pivot 91, on opposite sides of the frame 17, and their inner ends are rigidly connected by cross bar 149. The levers 145 and the cross bars 147 and 149 form a contact closing lever pivoted at 91, the levers 145 being spaced apart and disposed one on each side of the frame 17. A pivot pin 157 mounted in spaced projections 152 on the cross bar 149 of the closing lever, rotatably supports a roller 155 which is adapted to engage the knee of the main operating toggle to move the toggle to extended position to close the breaker upon clockwise movement of the closing lever 145.

Rotation of the operating handle 141 in a clockwise or closing direction, indicated by the arrow in Fig. 1, thrusts the link 151 downwardly and, due to the cooperation of the notched lower end of the link with the roller 153, rocks the contact closing lever 145 in a clockwise direction. During this movement, the roller 155 carried by the closing lever engages the link 93 of the now collapsed main toggle 93-95 and moves the toggle to its extended over-center position. Since, at this time, the tripping toggle 107-109 is over-center in its restraining position, the lever 89 is prevented from rotation, and consequently the force applied to straighten the toggle 93-95 rotates the contact arm 30 in a counterclockwise direction to close the contacts and tension the springs 85. The clockwise movement of the contact closing lever 145 and the roller 155 is sufficient to carry the toggle 93-95 over-center above the line 99-101 so that the contacts are held in their closed position until the breaker is again tripped.

As soon as the contacts are closed and the toggle 93-95 is moved to its over-center position, the handle 141 is released, whereupon a spring 159 tensioned between a projection on the frame 17 and the contact closing lever 145 rocks the lever counterclockwise, thrusting the link 151 up-

wardly and restoring the handle 141 to its neutral position (Fig. 1). The counterclockwise movement of the closing lever 145 is limited by the cross bar 149 striking the casing 138 of the shunt trip electromagnet.

The contact closing lever 145 may be operated to close the contacts automatically through the agency of a motor 139 mounted on a supporting plate 140 of insulating material secured to the frame 17. The motor 139 may be energized from any suitable source and in a manner well known in the art. When energized the motor is adapted, through the medium of suitable driving connection, to rotate a crank disk 130 which carries an antifriction roller 131. An arm 134 secured to the side of the contact closing lever 145 is provided with a cam face 132 normally disposed in the path of rotation of the roller 131.

When the disk 130 is rotated, upon energization of the motor 139, the antifriction roller engages the cam face 132 and rotates the arm 134 and the contact closing lever 145 in a clockwise direction to straighten the toggle 93-95 and close the contacts in the manner previously described. As soon as the roller 131 passes out of engagement with the arm 134, the spring 159 acts to restore the closing lever 145 to its normal position. The motor 139 is deenergized by a suitable limit switch (not shown).

The circuit breaker may be tripped manually by rotating the handle 141 through a small angle in a counterclockwise direction from its neutral position. Rotation of the handle in tripping direction causes a projection (not shown) on the link 151 to engage the previously described extension 121 on the yoke 119 of the toggle link 107, and move the tripping toggle 107-109 overcenter in a direction to cause its collapse. This permits the springs 85 to open the contacts in the previously described manner.

The trip device indicated generally at 133 (Figs. 1, 3 and 4) is operable to actuate the trip rod 135 after a time delay on overloads below a predetermined value, for example, approximately 1000% of normal rated current, and instantaneously on overloads above said predetermined value.

Referring to Figs. 2, 3 and 4, each pole of the trip device is of the same construction and comprises a laminated magnet core 161 secured by screw bolts 169 to a plate 171 of insulating material which is securely mounted on the base 11 by bolts 170. The magnet core 161 is U-shaped, at least as to a part of the laminations which extend transversely as at 82 and are surrounded by the coil 80 connected in series relation with the heater conductor 78 in the circuit of the breaker. Those laminations extending through the coil 80 are surrounded by an insulating tube 84 provided with end flanges 86 also of insulating material.

One end of the coil 80 is electrically secured to a connector 88 to which is also secured the lower end of heater conductor 78. The other end of the coil 80 is secured to the terminal connector 83 by a screw 92, the terminal 83 being securely mounted on the insulating plate 171 by means of screws 172. The lower end of the heater conductor 78 is secured to the connector 88 by a screw 96 and the connector is secured to a block 94 of insulating material by a screw 98.

The trip mechanism of each pole is supported in a frame comprising a pair of spaced substantially parallel plates 163 rigidly connected at their outer ends by a substantially horizontal cross member 165. The plates 163 have mounting feet

167 formed thereon through which the bolts 169 and 170 pass to rigidly secure the frame 163 to the magnet structure, the entire trip device being thus rigidly supported on the base 11.

5 A trip lever 173 comprising a pair of parallel levers connected at their outer ends by a cross member 177, is pivotally supported on a rod 175 mounted in the frame 163. The trip lever 173 carries an armature 179 comprising a pair of laminated armatures each securely riveted to one of the levers 173 and joined by armature frames 180 (Figs. 2, 3 and 4).

An adjusting screw 181 secured in the cross member 177 by means of a lock nut 183 is adapted to cooperate with an arm 185 mounted on a trip bar 187. The trip bar is rotatably supported in a bracket 189 on the casing 138 of the shunt trip electromagnet, and extends across all of the poles of the breaker. There is an arm 185 provided on the trip bar 187 for each pole and the center one of said arms is in line with the trip rod 135 and, as previously stated, is adapted upon operation of the trip bar by the trip device 133 for any one of the poles, to thrust the rod 135 upwardly to trip the breaker.

25 The trip lever 173 is normally biased against operation by the magnet core 161 by a pair of springs 191 but is adapted to be disconnected from the springs by a thermally responsive bimetal element 193 when the bimetal is heated a predetermined amount due to an overload current below the previously mentioned predetermined value. The bimetal element 193 is secured by means of rivets to a looped portion of the heater conductor 78 and the heater conductor is in turn secured to, but insulated from, a cross bar 194 extending between and supported by the frame members 163. This construction forms a rigid support for the bimetal element and the heater conductor.

30 The springs 191 have their lower ends hooked on a rod 196 mounted in spaced brackets 197 depending from the cross member 165 of the frame 163. The upper ends of the spring 191 are anchored on the ends of a rod 199 carried in the ends of a pair of spaced parallel arms 201 pivoted on the rod 175. The arms 201 are joined by an integral yoke 203. A spring 205 has one end connected to the yoke 203 and its other end connected to a pin 207 carried by the trip lever arms 173. This spring 205 serves to bias the trip lever 173 and armature 174 to normal unattracted position with a predetermined force independently of the springs 191 i. e. even though the trip lever is released from the springs 191.

35 The rigidly connected arms 201 and consequently the springs 191 are normally connected to the trip lever 173 by an antifriction latch 209 pivotally supported on the rod 199 and having a recess 211 therein normally embracing a latch roller 213 rotatably supported on a rod 215 supported in the trip lever 173.

40 Attraction of the armature 179 by the magnet core 161, when energized, tends to rotate the trip lever 173 in a counterclockwise direction. This force is applied through the roller 213 to the latch 209 in a direction to rotate the latch in unlatching or counterclockwise direction. This is normally prevented by a latch arm 217 pivoted on a rod 219 carried between the arms 201 and biased in latching direction by a spring 221. The lower end of the latch arm 217 is provided with a latch shoulder 223 releasably engaging a roller 224 rotatable on a pin 225 carried by the tail 227 of the latch 209.

It can be seen that as long as the latch arm 217 holds the latch 209 in latching engagement with the roller 213 and tension of the springs 191 is applied to the trip lever 173 biasing said lever against attraction by the electromagnet 161. The trip lever 173 is adapted to be unlatched from the influence of the springs 191 under the control of the bimetal element 193 when the bimetal is heated a predetermined amount in response to an overload current below the predetermined value.

When the bimetal 193 is heated a predetermined amount, it flexes upwardly, the free end thereof engaging a screw 229 adjustably secured in a bar 231 of insulating material secured to a yoke 233 integrally joining the arms 217, and rocks said arms counterclockwise. This movement of the arms 217 disengages the latch shoulder 223 from the roller 224 whereupon the counterclockwise force exerted by the trip lever 173 through the roller 213 disengages the latch 209 and permits operation of the trip lever by the magnet to trip the breaker. It will be noted that the major portion of the force transmitted by the roller 213 to the latch 209 is carried by the pivot 199 and only a small component of the force is applied through the roller 224 to the secondary latch 217. This is due to the fact that the moment arm tending to rotate the latch 209 in a releasing direction is small as compared to the lever arm or distance of the roller 224 from the pivot 199 of the latch 209. The result is that only a very small force is required of the bimetal element to move the secondary latch 217 to released position. The roller 224 reduces the latch friction to a minimum so that practically the only force that the bimetal is required to overcome is that of the small torsion resetting spring 221 which is very weak, and the bimetal adjusting spring.

The latch 209 is automatically operated to reconnect the springs 191 to the trip lever 173 upon restoration of the latter to its unattracted position. As soon as the electromagnet 161 is deenergized the spring 205 moves the armature 179 and the trip lever 173 clockwise to its unattracted position. As the latch roller 213 nears the end of its clockwise travel it engages a shoulder 214 on the latch 209 and rocks said latch clockwise about its pivot 199 engaging the latch 209 with the roller 213. As the bimetal 193 cools and resumes its normal position, the spring 221 rotates the latch arm 217 clockwise to engage the latch shoulder 223 with the roller 224.

The circuit breaker is calibrated for operation by the bimetal 193 by means of the calibrating screw 229, a lock nut being provided to lock the screw 229 in its correct adjusted position. The tripping characteristic or minimum overload current setting of the bimetal 193 may be manually adjusted by adjusting the tension of a spring 235 which biases the bimetal against tripping movement. This spring is connected at one end to a spring anchor 237 secured in the free end of the bimetal, and is connected at its other end to one end of an adjusting lever 239 of insulating material pivoted on the rod 196. The spring 235 biases the opposite end of the lever 239 against the tip of an adjusting screw 241 mounted in a projection 195 of the cross member 165. Obviously rotation of the screw 241 in one direction or the other will rotate the lever 239 about its pivot to increase or decrease the tension of the spring 235 depending on the direction of rotation of the screw.

The end 243 of the lever 239 forms a pointer and

projects through a vertical slot 245 in a U-shaped scale plate 247 which is adjustable vertically on spaced projections 249 of the cross member 165. The scale plate 247 is secured to the projection 249 by means of screws 251 which cooperate with vertical slots 253 in the scale plate. By loosening the screws, the scale plate may be slid up or down relative to the pointer 243 to assist in calibrating the device.

On overloads up to the predetermined value, that is, approximately ten times normal current, the pull of the magnet 161 is not sufficient to overcome the tension of the springs 191. If the overload persists, the bimetal becomes heated and when heated a predetermined amount rocks the latch arm 217 counterclockwise releasing the latch 209. The magnet core 161 now attracts the armature 179 rotating the trip lever 173 counterclockwise causing the latch 209 to rotate about its pivot 199 in the same direction. The combined force of the two springs 191 being much greater than that of the spring 205, the arms 201 are held in the position in which they are shown in Fig. 1. The spring 205 is stretched and acts to restore the trip lever 173 to its normal unattracted position (Fig. 1) when the electromagnet is deenergized. The parts are shown in Fig. 3 in the positions they assume when the breaker is tripped open in response to operation of one of the bimetal elements.

The strength of the spring 205 is such that the pull of the electromagnet 161—179 would be sufficient to move the trip lever to tripping position against the force of the spring alone at or slightly below the normal rated current of the breaker if the springs 191 were not connected to the trip lever by the latch 209.

Upon the occurrence of an overload above the predetermined value or a short circuit, the energization of the magnet 161 is sufficient to immediately attract the armature 179 and operate the trip lever 173 against the tension of the springs 191. In this event the latch arm 217 is not operated to unlatch the latch 209 and the parts move as a unit to the position in which they are shown in Fig. 4.

When the magnet is deenergized, the springs 191 act to restore the parts to their normal positions (Fig. 1).

Figures 5 and 6 illustrate a modified form of the invention. In this modification the secondary latch roller 224 carried by the latch 209 and the latch shoulder 223 on the arm 217 are omitted, and an inverted toggle comprising lever 259 and a U-shaped link 257 is provided to normally restrain the main latch 209 in latching position. The U-shaped link 257 straddles the arm 259 and is pivotally connected thereto by means of a pivot pin 261. The spaced arms of the U-shaped main latch 209 straddle the toggle link 257 and are pivotally connected thereto by the pin 225. The calibration of the trip device of the modification is effected by a threaded spring anchor 263 in the bimetal. This spring anchor is similar to the previously described spring anchor 237 with the exception that it is threaded and provided with adjusting and locking nuts 265. The remaining parts of the trip device illustrated in Figs. 5 and 6 are the same as the corresponding parts in the previously described mechanism and have been given the same reference characters.

Referring to Fig. 5 it can be seen that the center of the pin 261 is substantially on, or slightly to the left of a line drawn through the centers of the pins 219 and 225. With the toggle 257—259

in this position the latch 209 is held in position to restrain the trip lever 173 including the armature 179 in unattracted position.

When the bimetal 193 is heated a predetermined amount it flexes upwardly engaging the insulating element 231 and rocks the lever 259 counterclockwise about the pivot 219. This moves the pivot pin 261 to the right of the center line 219-225. The overload current which heats the bimetal 193 and causes it to flex also increases the energization of the electromagnet 161. This increases the pull of the magnet on the trip lever 173 which is applied in an upward direction to the latch 209 through the agency of the latch roller 213. Since the toggle 257-259 is now over center to the right of the line 219-225 the pull of the magnet rocks the latch 209 counterclockwise to release the trip lever 173 from the springs 191 and cause tripping of the breaker. This counterclockwise movement of the latch 209 rocks the link 257 counterclockwise about the pivot 261 and causes the lever 259 also to rotate in a counterclockwise direction about its pivot 219 against the tension of the spring 221. The counterclockwise movement of the latch 209, the link 257 and the lever 259 is limited by a yoke portion 266 of the link 257 striking a shoulder 267 on the arm 259. The parts are shown in their operated positions in Fig. 6.

As soon as the electromagnet 161 is deenergized the spring 205 rocks the trip lever 173 clockwise to its unattracted position. Near the end of the clockwise travel of the lever 173 the latch roller 213 strikes the shoulder 214 of the latch 209 and rocks said latch clockwise toward latching position. The latch 209 however, does not resume its full latching position until the bimetal 193 has cooled and assumed its normal position. As the bimetal cools it permits the spring 221, aided by the spring 205 through the agency of the roller 213, to rock the arm 259 clockwise to its normal position (Fig. 5). This movement straightens the toggle 257-259 and restores the latch 209 to its full latching position.

The front or right hand portion of the trip device is effectively insulated from the current carrying parts to prevent accidental contact with live parts, while the breaker is being adjusted. Reference to Figs. 3, 4, 5 and 6 discloses that the support bar 194 for the heater element 78 is insulated from the heater element thus insulating the frame 163 from the heater element. The member 231 and the adjusting lever 239, both of insulating material, insulates the latch mechanism from the bimetal element.

From the foregoing description it can be seen that the effort required of the bimetal element to operate the latch mechanism and cause tripping of the breaker has been reduced to a minimum. In fact the only force the bimetal has to overcome to effect tripping of the breaker is the tension of the comparatively weak spring 221. It can be further seen that the toggle and linkage structure of the operating mechanism (Fig. 1) greatly reduces the effort required of the trip device 133 to trip the breaker. The elimination or reduction of latch points and the provision of load-reducing devices permits the use of lighter parts and makes possible much faster operation of both the trip device and the operating mechanism, and, in addition, materially reduces the cost of manufacture.

Having described the several embodiments of the invention in accordance with the patent

statutes, it is to be understood that various changes and modifications may be made in the structural details disclosed without departing from some of the essential features of the invention. It is, therefore, desired that the language of the appended claims be given as reasonably broad interpretation as the prior art permits.

We claim as our invention:

1. In a circuit breaker, relatively movable contacts, operating mechanism for said contacts including an operating handle, a trip device comprising a trip lever pivoted intermediate its ends and operable to cause an opening operation of said contacts irrespective of the position of said handle, an electromagnet operable in response to predetermined circuit conditions to actuate the trip lever, a member pivoted coaxially with said trip lever, means biasing said member against operation, a latch mounted on said member for releasably connecting the member and the biasing means to the trip lever, a second latch mounted on said member normally restraining said first named latch in latching position, and a bimetal element operable in response to predetermined circuit conditions for actuating the second named latch to cause disconnection of the trip lever from the spring biased member.
2. In a circuit breaker, a switch member biased to open position, operating mechanism for said switch member, a trip device operable to cause an opening operation of said switch member, said trip device comprising a trip member, biasing means for opposing operation of the trip member, means releasably connecting the trip member to said biasing means, a latch for latching the connecting means in connecting position, and a bimetal element operable when heated a predetermined amount in response to overload currents below a predetermined value to operate said latch to a non-latching position, said electromagnet being operable in response to overload currents below said predetermined value to then move said connecting means to a disconnecting position, said electromagnet being operable in response to overload currents above said predetermined value to operate the trip member without disconnecting the biasing means.
3. In a circuit breaker, a switch member biased to open position, operating mechanism for said switch member including an operating handle, a trip device comprising a trip member pivoted intermediate its ends and movable to cause an opening operation of said switch member irrespective of the position of said operating handle, an electromagnet responsive to overload currents for operating said trip member, a pivoted arm, biasing means attached to said arm, a member pivoted on said arm for connecting and disconnecting the biasing means and the trip member, a latch pivotally supported on said arm and operable to cause disconnection of said trip member from the biasing means, a thermally responsive means operable in response to overload currents for operating the latch, and a spring connected at one end to the trip member and at its other end to the pivoted arm for biasing the trip member to unoperated position at least when the biasing means is disconnected therefrom.
4. In a circuit breaker, relatively movable contacts, operating mechanism including a linkage operable to cause opening of said contacts, a trip device comprising a trip lever operable to actuate said linkage, an electromagnet operable in response to overloads to operate the trip lever,

means biasing the trip lever against operation, a latch normally connecting said biasing means to said trip lever, said latch being operable to unlatching position by the force exerted thereon by said electromagnet to disconnect the biasing means, a second latch normally preventing unlatching movement of said first named latch, a bimetal element operable in response to overload currents below a predetermined value for moving the second named latch to unlatch the first named latch to permit said electromagnet to disconnect said biasing means, and said electromagnet operating said trip lever to tripping position against the force of said biasing means to instantaneously trip the breaker in response to overload currents above said predetermined value.

5. In a circuit breaker, relatively movable contacts, operating mechanism for said contacts including an operating handle, a trip device including a trip member operable to cause an opening operation of the contacts irrespective of the position of said handle, an electromagnet responsive to predetermined circuit conditions for actuating the trip member, spring biasing means opposing operation of the trip member, means releasably connecting the biasing means to the trip member, said connecting means being operable to disconnecting position by the force of said electromagnet, to release the trip member from the biasing means, means for positively restraining the connecting means in connecting position, and a thermally responsive element operable when heated a predetermined amount in response to overload currents below a predetermined value to move the restraining means to a position wherein it is ineffective to restrain the connecting means in connecting position to thereby permit said electromagnet to move said disconnecting means to disconnecting position, and said electromagnet operating said trip member without disconnecting the biasing means to instantaneously trip the breaker in response to overloads above said predetermined value.

6. In a circuit breaker, relatively movable contacts, operating mechanism for said contacts, a trip device, including a trip member operable to cause an opening operation of the contacts, an electromagnet responsive to predetermined circuit conditions to actuate the trip member, biasing means comprising a spring opposing operation of the trip member, means releasably connecting the biasing means to the trip member, said means being operable to release the trip member from the biasing means, a toggle releasably restraining the connecting means in connecting position, and a bimetal element heated in response to overload currents and operable when heated a predetermined amount to operate said toggle to a non-restraining position.

7. In a circuit breaker, a switch member biased to open position, operating mechanism for said switch member, a trip device comprising a trip member pivoted intermediate its ends and operable to cause an opening operation of the operating mechanism, electromagnetic means for operating the trip member in response to overload currents, biasing means comprising a spring opposing operation of the trip member, a latch normally connecting said biasing means to the trip member, a toggle normally restraining said latch in latching position, said toggle being operable under certain circuit conditions to cause disconnection of the trip member from the biasing means, and current responsive thermal means operable in response to predetermined circuit conditions to operate said toggle, said biasing means remaining connected to said trip member when said member is operated in response to overloads above a predetermined value.

8. In a circuit breaker, relatively movable contacts, operating mechanism for said contacts, a trip device including a trip member operable to cause opening of the contacts, biasing means comprising a spring normally opposing operation of the trip member, means comprising a latch for releasably connecting the biasing means to the trip member, a toggle connected to said latch for normally restraining said latch in latching position, said toggle being and operable to cause disconnection of the trip member from the biasing means, and a bimetal element operable when heated a predetermined amount in response to overloads below a predetermined amount for operating the toggle, said bimetal element constituting the sole means for effecting disconnection of the trip member from the biasing means.

9. In a circuit breaker, relatively movable contacts, operating mechanism for said contacts, a trip device comprising a pivoted trip lever operable to cause an opening operation of said contacts, an electromagnet operable in response to overload currents to operate said trip lever, a member pivoted coaxially with said trip lever, means comprising a spring biasing said member against operation, a latch member pivotally supported by said member for connecting said member to the trip lever, means supported by said member biased to a position for restraining said latch in latching position, a bimetal element operable in response to predetermined overload conditions to operate said restraining means to a non-restraining position to effect disconnection of the biasing means from the trip lever, and means for adjusting the operating characteristics of said bimetal element.

TURE LINDSTROM.
JOHN W. MAY.
